[57] **CLAIM**

The ornamental design for a battery package, as shown and described.

DESCRIPTION

FIG. 1 is a top perspective view of the battery package of this invention in an open configuration, with an array of batteries located therein shown as environmental material, the batteries forming no part of the claimed design;

FIG. 2 is a front elevational view thereof, in a closed configuration;

FIG. 3 is a rear elevational view thereof;

FIG. 4 is a left side elevational view thereof, the right side elevational view being a mirror image thereof;

FIG. 5 is a top plan view; and,

FIG. 6 is a bottom plan view.
